[57] **CLAIM**

The ornamental design for a trash bag support, as shown and described.

DESCRIPTION

FIG. 1 is a top and front perspective view of a trash bag support showing my new design, the broken lines are for illustrative purposes only;

FIG. 2 is a side elevational view thereof, the opposite side elevational view being a mirror image of that shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a top and front perspective view of a second embodiment of the trash bag support; and,

FIG. 8 is a side elevational view of FIG. 7, the opposite side elevational view being a mirror image of that shown.

The sole difference between the first and second embodiment being in the different height of the trash bag support.
